ELECTRIC RELAY, PARTICULARLY FOR
PURPOSES OF TELEVISIONKurt Schlesinger, Berlin, Germany, assignor, by
mesne assignments, to Loewe Radio, Inc., a cor-
poration of New YorkApplication August 5, 1933, Serial No. 683,735
In Germany August 6, 1932

2 Claims. (Cl. 178—69.5)

My present invention relates to television systems, and has for its object to provide synchronization at the end of each scanned line and after the scanning of each image. According to my invention, that section of the receiver which controls the scanning is constructed in such a manner that during the major portion of the time during which line-scanning and image-scanning takes place, such section will be blocked against the passage of impulses attaining the relatively high voltage employed for synchronizing impulses, and will assume a waiting position only at the end of each line and of each image. In other words, the voltage employed for the synchronizing impulses is higher than the one of the impulses used for the transmission of image-points, and the apparatus is responsive to such impulses of relatively high voltage only at the end of each line and of each image. I thus avoid the possibility of accidentally allowing the passage of voltages high enough to affect the synchronizing devices, at the wrong moment, that is before the end of a line or image is reached. In the absence of provisions for blocking the passage of high-voltage impulses during the transmission of image points, the synchronizing devices might be operated at the wrong time, for instance if some portions of the image should produce impulses of abnormally great strength.

In the present specification I have described, as an example of my invention, an electrical relay, which enables electrical impulses of exactly given value and duration to be obtained at the receiving end when, proceeding from the transmitter, a certain threshold potential is produced or exceeded. According to the invention, there is employed as a relay an electrical tilting or deflecting arrangement, preferably one having a grid-controlled tilting or deflecting tube, to the grid of which there is applied, in accordance with the invention, a constant bias and also the control potential.

It is possible in this manner to obtain impulses, the form of which is constant, irrespective of the nature of the impulse potential proceeding from the transmitter after the threshold value has been exceeded. It is also possible in this fashion to produce a relay, which after a definite and adjustable period of closing again opens automatically, and then after a likewise adjustable delay is again sensitive to impulses, so that, if necessary, external impulse potentials are able to act on the relay only after this recovery period has expired.

The constructions illustrated by the accompanying drawing show an arrangement embodying the invention and effecting the interruption or blocking of the anode current with the aid of a circuit producing free tilting oscillations. 5

In said drawing, Fig. 1 is a diagram illustrating the principle of my invention, while Fig. 2 shows a detail and Fig. 3 a circuit diagram of an apparatus or system embodying said invention.

In Fig. 1, a gas-filled grid glow tube 1 having a hot cathode 2 (for instance, one heated by a heater filament H), is situated in parallel with a relatively small blocking condenser 3, which is charged through the medium of a resistance 4 by a D. C. potential source for instance a battery 15 5. The grid 6 of this glow tube is connected through the medium of a high ohmic resistance 1 with the negative terminal of an additional battery 8, and is, therefore, furnished with a negative bias of such extent that discharge of 20 the condenser 3 is unable to take place over the glow path. Now it will be clear that any desired potential which is supplied by a remote source of signalling potential 9 and is conducted to the relay over the line 10 will be compelled to act 25 on this glow relay immediately the potential exceeds the ignition surge of the grid potential. The latter is of a definite kind if the potential of the battery 5 and the reciprocal of the tube 1 are known, and may be adjusted exactly to with- 30 in a few tenths of a volt to any desired selected value by a corresponding choice of the bias 8. If the relay has once been actuated, the condenser 3 will be discharged in a period of time which is proportional to its capacity and the internal resistance of the path of the glow arc. This period of time may be made very short, and is an invariable constant of the relay. If the condenser has been discharged, recharging takes 35 place over the resistance 4 in a period of time 40 which may be regulated by varying the value of 4. If now after completion of the recharging operation the grid potential of 6 is still above the ignition value, a new tilting or deflecting action takes place. If on the other hand the grid 45 potential has again fallen within this period below the surge value, the relay remains in the position of waiting until the same is acted upon by a new impulse.

With suitable dimensioning of the condenser 3 50 it is possible to produce with this connection tilting or deflecting frequencies of up to 200,000 periods and more. If now an ampere-meter or a corresponding recording or indicating instrument A is placed in the charging connection of 55

- the tilting tube, the same, for such time as a control impulse exceeding the surge value is present at the grid 6, records a constant current, which corresponds with the median value derived from charging current and discharge current of the tilting or deflecting apparatus. The relay according to the invention is, therefore, readily capable of use in the form of embodiment according to Fig. 1 for telegraphic transmitters, wireless calling apparatus and the like. Naturally in place of the gas-filled grid glow tubes with hot cathodes it is also possible to employ other glow tubes, more particularly such as are grid-controlled.
- 15 It is also quite readily possible in accordance with the invention to combine the relay with a tuned receiving circuit, and in this manner to produce automatically recording wireless apparatus of all kinds.
- 20 It is, however, particularly convenient to employ the relay according to the invention for synchronising television reception from the contents of the picture. In this connection it is assumed that the high-frequency mixture from the television transmitter includes both image impulses and line impulses, which may be obtained, for example, by the use of a Nipkow disc as scanning means in conjunction with a double edge 4, 5 (Fig. 2) of the image being scanned. This edge may either be darker or lighter than the remainder of the picture. According to the invention, it is particularly convenient to produce the said edge by additional intense illumination of the edge of the image.
- 30 As regards the synchronisation of television images, the connection system illustrated in Fig. 3 has been found to be particularly suitable.
- In this connection system there is provided in the first place a glow relay 1, such as already described, but combined with a preliminary tube 2 connected in peculiar fashion. The preliminary tube is a high-vacuum rectifier tube, which requires to contain merely two electrodes. The same together with a high ohmic parallel resistance 3 of suitable size is connected in series with the static (constant) bias of the grid 4 of the glow lamp 1, which bias is adjusted once and for all at the grid battery 5. The operation of the preliminary tube arrangement 2, 3 in conjunction with a transmission condenser 6 has already been described in an earlier application, and amounts to a measurement of the peak potential supplied by the transmitter, i. e., the arrangement operates in such fashion that the condenser 6 on each occasion endeavours to take up a charge up to the maximum amplitude of the potential proceeding from the transmitter. This charging potential, however, is not quite reached by the condenser, the latter lagging behind the potential all the more the smaller the leakage resistance 3. On the other hand the condenser attains its stationary condition of charge all the more quickly the smaller it is itself and the greater the emissive power of the rectifier tube 2. For this tube there is preferably selected a modern high-vacuum tube with oxide cathode and indirect, well-insulated heating, a heater element being indicated at H'. The result of the action of 2, 3 and 6 is, therefore, that the grid potential of the glow tube 1 is always smaller to a definite extent than the maximum peak occurring during signalling. If in addition the grid potential is so adjusted at the battery 5 that the excess amount received from the transmitter is sufficient to actuate the

glow tube 1, the arrangement may successfully be employed in the following manner for the synchronisation of a television receiver:

The time constant of 2 and 6 is made to be smaller than the transmission impulse period τ_s —approximately $\frac{1}{20}$ line period. This corresponds with an impulse duration of approximately 5 image points, in which connection allowance has also been made for an increase in the desired line impulse due to the action of the transmission apparatus. Owing to the stated dimensioning: internal resistance R_1 of 2 approximately 100,000 ohms, capacity of C_6 approximately 100 cm., i. e., $\tau_{2,6}$ —approximately 10^{-5} seconds the amplitude filter is able even during the short transmission line impulse to accommodate and adjust itself to the maximum value thereof. The once adjusted potential remains at the grid of the glow tube 1 only during the period $\tau_{6,3} = C_6 R_3$. This period is preferably adjusted to approximately half of the line period, which is effected, for example, by means of a resistance R_3 of a few megohms. In this manner it is accomplished that occasional strong image content potentials are blocked off from the tilting or deflecting relay during the recordal of a line, and that the tilting or deflecting relay is sensitive to impulses only at the end of the line. The relay itself after reception of the line impulse at the grid 4 is tilted or deflected with an extremely short period of tilting or deflecting $\tau \leq 10^{-6}$ seconds, corresponding at the most with the duration of one image point, which is readily obtained by means of a small condenser 7 of approximately 100 cm. This tilting or deflecting impulse acts on the line 8, at the end of which there is situated a simple frequency filter 9, 10 or 11, 12. The very short natural impulse per line does not produce any appreciable potential parallel to the condenser 10 of approximately 10,000 cm., which is connected in series with the resistance 9 of approximately 100,000 ohms; on the other hand the potential occurs with full force at the terminals of the resistance 12 behind a condenser 11 of approximately 10,000 cm. At the resistance 12, however, there is connected (as indicated by ZK) the line tilting or deflecting device of the television receiver, which is therefore actuated. This tilting or deflecting device may naturally be either a self-oscillating or a self-suspended tilting or deflecting device assuming a position of waiting until arrival of the line impulse.

With suitable dimensioning of the charging resistance 13 it is possible in the case of the arrangement as described to perform simultaneous initiation of the image change without requiring any additional apparatus. This occurs as follows: Owing to the doubled shuttering of two edges of the image as described and illustrated in Fig. 2 there exists at the transmission end upon a change of image an interval (between signals) of the duration of several lines. Under certain circumstances this interval may be interrupted by providing in the diaphragm a stretched portion or extension 6, which may also consist of a semi-transparent material and is employed for maintaining the line synchronism. During this interval in transmission the receiver which, as assumed, operates if desired with reversal of the phase, takes up a maximum potential for a relatively long period, the grid of the glow tube 1 accordingly remains positive for a long time, and the relay 1, 7, 13 performs, therefore, during the whole of this time free tilting or deflecting oscil-

lations, the frequency of which is the greater, the smaller the resistance 13. Owing to these oscillations, however, the medium potential of the condenser 7 will be lowered the more as compared 5 with the full battery potential, the greater the frequency of the tilting or deflecting oscillations. This lengthy drop in potential causes a wave advancing along the line 8, from which wave, owing to its greater duration, a sufficient part-potential 10 reaches the condenser 10. From this point, however, an impulse is transmitted (through the connection indicated at BK) to the image or field or frame change tilting or deflecting apparatus and the change of image caused.

15 It may be pointed out that a device such as shown in Fig. 3 may also reproduce without distortion images emanating from television transmitters of that kind in which, owing to certain distribution errors in the transmission disc, the 20 line impulses are not strictly periodical. In particular, owing to the filtering of the amplitude, which from a chronological aspect takes effect practically only periodically, the disadvantage is avoided that the synchronising signals may be 25 disturbed by the image signals.

What I claim as new and desire to secure by Letters Patent is:

1. In a television system including a receiver,

line and image changing circuits, means rendered operable by synchronizing impulses received by said receiver for controlling said circuits, comprising a triode, a source of potential connected to cathode and anode circuits of said triode, a 5 condenser between said source and said triode circuits, said condenser being connected to the input of said line and image-changing circuits for actuating them upon discharge thereof through said triode, the grid of said triode being normally 10 negatively biased to prevent the discharge of said condenser through said triode, said grid being connected to the output of said receiver for allowing said condenser to discharge through said tube 15 throughout the period when said grid is rendered positive by said synchronizing impulses.

2. In a television system as claimed in claim 1, including a level maintaining device for blocking off impulses from said grid during intermissions between said synchronizing signals, said 20 level maintaining device comprising a thermionic diode shunted by a leak resistance, another condenser, the anode of said diode being connected by said other condenser to the output of said receiver, said anode also being connected to the grid 25 of said triode, the cathode of said diode having a negative bias.
